UNITED STATES PATENT OFFICE.

HENRY H. FORSYTH AND GEORGE H. FORSYTH, OF CHICAGO, ILLINOIS,
ASSIGNORS TO THE CURTAIN SUPPLY COMPANY, OF SAME PLACE
AND JERSEY CITY, NEW JERSEY.

SHADE ADJUSTING AND HOLDING MECHANISM.

SPECIFICATION forming part of Letters Patent No. 684,214, dated October 8, 1901.

Application filed April 4, 1896. Serial No. 586,248. (No model.)

To all whom it may concern:

Be it known that we, HENRY H. FORSYTH and GEORGE H. FORSYTH, of Chicago, Illinois, have invented certain new and useful Improvements in Shade Adjusting and Holding Mechanisms, of which the following is a specification.

This invention relates to that class of devices which are used to hold spring-actuated window shades or curtains in any position to which they may be adjusted, and more particularly to that class of shade-holding devices in which cords are employed as the means for guiding and holding the shade.

The object of the invention is to provide means of this kind which shall be very simple in construction and operation and therefore economical, readily applied, and easily removed or repaired.

In the accompanying drawings, Figure 1 is an elevation, partly in section, through one side of a window-casing. Fig. 2 is a transverse sectional view; and Fig. 3, an enlarged detail showing one end of the shade-stick in side elevation. Fig. 4 is an end view thereof, and Fig. 5 is a detail view of a looped end of the cord and a collar used therewith. Figs. 6 and 7 are detail views showing the endless cord passing through apertures of the tip or head.

In the drawings, A represents the curtain, which is mounted on the usual spring-actuated shade-roller B and is provided in its lower edge with a shade-stick C. Said shade-stick in the form shown has a tubular body, and light spiral springs D are arranged in the ends of said tubular body and have a bearing thereon. Within the outer ends of the tubular-body sections C are arranged sliding tubes E, having a slot-and-pin connection with said tubular body, the slot being marked c and the pin e. Within the outer ends of the tubes E work the stems f of a tip F, said tip having on its outer end jaws or lugs f', with a vertical slot between said jaws or lugs. The tip or head F has also the perforated lugs F'. To these lugs F' is connected an endless cord, which is doubled upon itself and passes over pulleys, by which it is guided and controlled. In the illustration shown in

the drawings and which is the preferred form the pulleys are located at the four corners of the frame and are marked in series G, H, I, and J. The cord K may be attached to the lugs of the tip or head without severing said cord by passing it through the apertures of the lug, as shown in Figs. 6 and 7, the friction of the cord being sufficient to prevent its slipping through the head; but in the form shown in Figs. 1, 2, and 5 two of the strands of the cord are severed and the four severed ends are secured to the tips or heads by being passed through the apertures of the lugs F' and doubled upon the body of the cord and secured thereto by the keepers or split collars k. (Shown in Fig. 5.) The pulleys are located in grooves L, formed in the window-stops, and the vertical strands of the cords may be entirely concealed therein. In order to prevent the strands of the cord which are not attached to the heads F' from coming out of the grooves, said strands pass between the lugs f' and are thereby held within the groove. Now it will be obvious that upon raising or lowering the shade by applying sufficient force to its lower margin to overcome the frictional resistance of the cord the strands which are attached to the tips or heads will ascend or descend, according to the direction of movement, while the other strands of the cords will move in the opposite direction. There are two of the pulleys G and two of the pulleys H. Following the strands around these various pulleys the strand attached to the upper of the lugs F' on the right-hand end of the fixture passes up over the rear member of the pair of pulleys H, thence over the rear one of the pulleys G, thence down between the lugs f' on the opposite tip or head and around the pulley I from its rear side, thence up, and is made fast to the lower of the lugs F' at the left-hand end of the shade-stick. The strand which is made fast to the upper of the lugs F' at the left-hand side of the shade passes up over the front member of the pair of pulleys G, thence over the front member of the pair of pulleys H, thence down between the lugs f' of the tip at the right-hand side of the shade, thence down around the pulley J from

the rear and up to the lower lug F' at the same side of the shade. Now obviously when the shade is moved up the pull is equal on both ends, no matter where the force be applied, and the same is true when the pull is in a downward direction, it thus being impossible to move the curtain out of its horizontal position, while the heads or tips projecting in the grooves prevent its being moved out of its normal plane. Thus there is provided on each side of the shade an ascending and a descending strand of the cord and all of the strands move simultaneously and in unison, two of the strands ascending while the others are descending. The inside strands move in one direction and the outside strands move in the opposite direction, the inside strands being attached to the shade-stick. If it be desired to disconnect the shade from the operating-cord, it may be readily done by forcing the tube E inwardly, compressing its spring until the stem f clears the end of such sliding tube. Both ends may be similarly disconnected, and by this simple means the shade can be removed and any of the parts renewed or repaired and the window exposed for cleaning.

While the arrangement shown is preferred, obviously it may be changed within the scope of the invention. For example, the strands which are shown as passing across the top of the window may be arranged to cross at the bottom instead and instead of running around three sides of the window the cords may be extended entirely around the window. These and other similar variations in the arrangement of the parts may be made while preserving the essential features of our invention, as will be pointed out in the claims. The matter of connecting the cord to the curtain may also be varied.

Our invention is adapted for general use, but especially adapted for use in street-railway cars, where economy and simplicity in construction and ease of working are much desired. The construction described to facilitate the disconnecting of the shade from the cord also permits of the use of our invention when there is a wide range of variation in the depths of the grooves, in the width or distance between the bottoms of the grooves, or other inaccuracies or variations in the construction of the window or shade. This is accomplished by having the sliding sections E backed up by the springs D, which at all times maintain the tips within the grooves, and thereby maintain the shade in its normal vertical plane and insures the retention of the outer strands of the cord within the grooves. In the use of these devices a certain amount of slack will be produced, which may be taken up from time to time by releasing any one of the attached ends and drawing upon it until the slack is taken up and again fastening the cord. Obviously it is only necessary to release the cord at one place in order to take up the slack at its outer end, the cord being

continuous. It will be observed also that the slack will be distributed throughout the length of the cord and that there is no unequal strain or wear upon any portion of the cord. It will be noticed that the lower pulleys are set in housings N, fitted into recesses in the grooves, so that a large roller can be used and yet confined within the depth of the slot. The upper rollers are mounted in triangular housings O, which furnish a bearing for each pair of pulleys and which housing is readily mounted in the angle of the frame, the pair of pulleys running on a common spindle and preferably with a washer between them.

We do not limit our invention to the precise details of construction shown and described. That feature of the invention relative to the provision of means whereby the shade may be readily disconnected from the shade-operating cords is important. These detachable heads may be constructed in various ways.

We claim—

1. In a shade-holding mechanism, the combination with a shade-stick having a longitudinally-sliding section, a spring tending to thrust said section outwardly, a tip or head mounted upon the sliding section, and an adjusting-cord connected to the tip, substantially as described.

2. In a shade-holding mechanism, the combination with a shade-stick having a longitudinally-sliding section, a spring tending to thrust said section outwardly and a tip or head detachably connected to said sliding sections, substantially as described.

3. In a shade-holding mechanism, the combination with a shade-stick composed of a tubular body, longitudinally-sliding tubular sections telescoped with the body and having also a slot-and-pin connection therewith, springs seated within the hollow of the body and bearing upon said sliding sections and tips or heads having shanks sliding within said sections, substantially as described.

4. The combination with a shade-stick having a plurality of sections movable endwise with relation to each other, and tips or heads detachably connected with the sliding sections, said tips having projecting lugs separated to provide vertical grooves and an adjusting mechanism consisting of an endless cord doubled upon itself, two of the strands whereof are attached to said tips or heads and the remaining strands whereof are guided in the grooves thereof, substantially as described.

5. In a shade holding and adjusting mechanism, the combination with the shade having a shade-stick provided with spring-mounted heads, an endless cord doubled upon itself, single guide-pulleys arranged at the bottom of the frame over which the strands are turned and said strands leading across the top of the windows and double pulleys arranged at the upper corners of the window

and adapted each to receive strands of the running cord, substantially as described.

6. In a shade-holding mechanism the combination with a shade-stick, of tips or heads having a telescoping connection with said shade-stick and outwardly-forcing springs carried by the shade-stick and adapted to press said tips or heads outwardly, and op-

erating-cords connected with said tips or heads, substantially as described.
